UNITED STATES PATENT OFFICE.

OSCAR BOND, OF SAPULPA, OKLAHOMA.

TORPEDO HOOK.

Application filed January 23, 1926. Serial No. 83,378.

This invention relates to a torpedo hook especially designed for use in lowering torpedoes or shells filled with nitroglycerin or other explosive into oil or gas wells in carrying out what is known as the "shooting" of said wells.

The object of the present invention is to provide a torpedo hook which will prevent premature explosions and which insures a discharge of the shell or torpedo from the hook and the explosion of the same at the proper point in the well.

A further object is to provide a torpedo hook wherein the torpedo is firmly and securely held and locked to the hook during the entire time that the torpedo is being lowered into the well but which also permits the release of the torpedo under the control of the operator above the ground when the torpedo has reached the proper point in the well.

A further object is to provide a device of this character and having these safety features and which is also of simple and durable construction, reliable and efficient in operation, and easy and comparatively inexpensive to manufacture.

Other objects and advantages reside in certain novel features of the construction, arrangement and combination of parts which will be hereinafter more fully described and particularly pointed out in the appended claims, reference being had to the accompanying drawings forming a part of this specification, and in which:

Figure 1 is a view in side elevation showing a torpedo hook constructed in accordance with the present invention,

Figure 2 is a view thereof in front elevation,

Figure 3 is a view in side elevation looking at the opposite side of the hook from that viewed in Figure 1, and

Figure 4 is a fragmentary view, partly in section and partly in elevation showing the internal construction of the hook.

Referring to the drawings it will be seen that the torpedo hook embodying the present invention includes a hanger frame, designated generally at 1, and made up of a body portion 2 and spaced side bars 3. The body portion 2 is provided with an opening 4 to facilitate the connection of a lowering line or the like to the hanger frame.

A flat and elongated hook body 5 is slid-

ably fitted in between the flattened lower ends 6 of the side bars 3 of the hanger frame. The upper portion of the body 5 is formed with a lengthwise slot 7 through which a pin 8 secured to the ends 6 of the side bars extends, whereby the hanger frame and the hook body are interfit for limited sliding movement.

The hook body 5 is pulled upwardly relative to the hanger frame by means of a retractile coil spring 10 having one end connected, as at 11, to the body portion of the hanger frame and having its other end connected, as at 12, to the upper end of the hook body 5.

The upward movement of the hook body relative to the hanger frame is limited by means of an adjustable abutment carried on the hook body and engageable with the hanger frame, the adjustable abutment 75 preferably consisting of a screw 15 engageable with the hanger frame and adjustably connected with a post 16 fixed on the hook body 5.

For the purpose of providing torpedo 80 supporting means the hook body 5 is enlarged at its lower end and is formed with an inclined slot 18, the slot 18 inclining from a point intermediate the opposite sides of the hook body upwardly and laterally through one side thereof. In this way the slot 18 provides a bill 19 and due to its inclination also provides for the automatic disengagement of the hook from the torpedo upon relative downward movement 90 of the hook relative to the torpedo.

Means is provided for preventing disengagement of the hook and torpedo until the torpedo has reached the point in the well where it is desirable to explode the same and this means preferably includes a locking bar 20 slidably mounted in a guideway 21 in the hook body and adapted to be projected across the slot 18 or to be withdrawn entirely into the guideway 21. The weight 100 of the bar 20 tends to urge the same to the position shown in Figure 4 wherein it locks the torpedo in the slot 18.

Release mechanism is provided for the locking bar 20 and comprises a shaft 22 rotatably mounted in bearings provided therefor in the hook body 5 and having a pinion 23 formed thereon and meshing with a rack 24 formed on the bar 18 (see Fig. 4). One end of the shaft 22 projects be-

yond the hook body and has a ratchet wheel 25 fixed thereto. A pawl 26 is co-operable with the ratchet wheel 25 and is fixed to and carried by one of the enlarged lower ends 5 of the side bar 3 of the hanger frame. The pawl 26 is resilient so that when the pawl moves downwardly with the hanger frame it plays idly over the teeth of the ratchet wheel 25 but due to the hook or 10 arrow-shaped formation of its head 26^a the pawl turns the ratchet wheel 25 when the hanger frame moves upwardly relative to the hook body.

Retrograde movement of the shaft 22 is 15 prevented by means of a spring detent 27 secured to the hook body, as at 28, and bent about the post 29 so that its outer end is tensioned for engagement with the teeth of the ratchet wheel 25.

20 With this arrangement when the hook is to be used the hanger frame and hook body are manipulated to withdraw the locking bar 20 from the slot 18 to permit the torpedo or its supporting part to be engaged 25 with the slot 18. The pawl 26 is then flexed away from the ratchet wheel 25 and the locking bar 20 descends under the influence of gravity until it blocks the slot 18 as shown in Figure 4. The torpedo may 30 now be lowered into the well and even though it be hung temporarily on obstructions in the well bore it will not be disengaged from the slot 18 due to the action of the bar 20. However, when the bottom 35 of the well has been reached and the torpedo or shell rests thereon the bar 20 may be withdrawn from across the slot 18 by simply raising and lowering the hook. It is to be understood at this time that during 40 the lowering of the torpedo the spring 10 is stretched due to the weight of the torpedo exerted on the spring through the hook 5. When the torpedo rests on the bottom of 45 the well its weight is no longer exerted on the hook 5 and consequently this body is drawn upwardly by the spring 10 which causes the pawl 26 to pass downwardly over the ratchet wheel 25. By elevating the hook at this time the hanger frame is moved 50 upwardly relative to the hook body and the pawl 26 co-acts with the ratchet wheel 25 to rotate the same. By repeating this operation the shaft 22 is turned to such an

extent as to entirely withdraw the bar 20 from the slot 18.

55

I claim:

1. A torpedo hook comprising a hanger frame, a hook body slidably mounted on the hanger frame and having torpedo supporting means, spring means for pulling the hook body upwardly on the hanger frame, a locking bar for preventing disengagement of the torpedo and its supporting means, a release for said locking bar operable by the relative movement of the hanger frame and hook body and comprising a shaft rotatably mounted on the hook body, motion transmission means between the shaft and the bar, a ratchet wheel fixed on the shaft, a pawl carried by the hanger frame and co-operable with the ratchet wheel and a detent co-operable with the ratchet wheel to hold the same against retrograde movement.

65

2. A torpedo hook comprising a hanger frame, a hook body slidably mounted on the hanger frame and having torpedo supporting means, spring means for pulling the hook body upwardly on the hanger frame, a locking bar for preventing disengagement of the torpedo and its supporting means, a release for said locking bar operable by the relative movement of the hanger frame and hook body and comprising a shaft rotatably mounted on the hook body, motion transmission means between the shaft and the bar, comprising a pinion fixed on the shaft, a rack formed on the bar and meshed with the pinion, a ratchet wheel fixed on the shaft, a pawl carried by the hanger frame and co-operable with the ratchet wheel, and a detent co-operable with the ratchet wheel to hold the same against retrograde movement.

70

3. A torpedo hook comprising a hanger frame and hook body interfitting for limited relative movement, said hook body having torpedo supporting means, a shiftable locking bar for preventing disengagement of the torpedo and said supporting means, a release for said bar including a shaft geared to the bar, and a pawl and ratchet drive for the shaft operable upon relative movement of the hanger frame and hook body.
